ABSTRACT

Glare shielding device as for night driving motorists in which two shields are supported by a foldable frame so as to be interposed in the wearer's normal line of vision forwardly of his eyes and offset from the pupillary axes thereof to impede light from the oncoming traffic directly striking the wearer's eyes while permitting him to have substantially full straight ahead and also lateral vision, the frame and shields being a unitary molded piece of translucent plastic material.

GLARE SHIELDING DEVICE

This invention relates to glare shielding devices and particularly those of the type which are worn by motorists and/or their passengers when driving at night or when facing into the sun.

A first and principal object of the invention is to provide a glare shielding device which will provide a maximum amount of uninterrupted straight ahead vision when worn, while also shielding or shading the wearer's eyes against the glare from headlights of oncoming traffic when driving at night or from sunlight when driving into the sun.

A second, equally important object of the invention is to provide such a shielding device which also may be mass produced at low unit cost and will be of a durable rugged construction.

In the accomplishment of these objects, a shielding device according to the invention comprises a brow bar which extends across the wearer's forehead above his eyes and has means by which it is stably supported on the wearer's head and supports a pair of spaced apart light impeding members or shields forwardly of the wearer's eyes in a particular relation such as to impede the passage of light from the oncoming traffic to the wearer's eyes without restricting his straight ahead vision and while also affording him lateral vision as well.

It is a feature of the invention that the light impeding members or shields may be supported on a wearer's head at a distance forwardly of the wearer's eyes and in offset relation to both the wearer's eyes so as to provide the desired shielding effect without the wearer suffering discomfort or being made unduly aware of their presence.

In accordance with the invention said light impeding members or shields may be either opaque or of translucent material. However, when translucent they provide the advantage of impeding or cutting down the intensity of light from the headlights of the oncoming traffic, but without the wearer losing his visibility thereof. This the inventor has found to be psychologically advantageous.

A further feature of the invention is that the two shields or light impeding members are spaced apart in offset relation to the wearer's straight ahead vision and also at a distance forwardly of his eyes such that they are an effective impediment to the passage of light to the wearer's eyes from oncoming traffic in the adjacent lane, whether the oncoming traffic is close to or at a distance from the motorist.

Still another feature of the invention is that the two shields are so dimensioned and shaped that while they are effective to impede passage of light from the headlights of oncoming traffic in the adjacent lane, whether up close to or at a distance down the road, at the same time they provide only minimum encroachment on the motorist's view of his own lane. They also do not noticeably interrupt the motorist's lateral vision.

Still another feature of the invention is that in its preferred form the shielding device comprises an articulate structure which may be molded as a unitary piece of translucent plastic material having hinged parts so related that the device can be stably supported on the average wearer's head and will also hold the shields in a fixed predetermined offset relation forwardly of the wearer's eyes so as to be effective against glare from oncoming traffic while permitting him a nearly full uninterrupted angle of viewing.

Still another feature of the invention is that the construction and relation of the parts comprising the shielding device are such that the device may be folded into a compact unit for packaging purposes and/or for storage in a case or other container to be kept in the glove compartment of the motorist's vehicle.

Many other objects, advantages and features of the invention will be at once apparent, or will become so upon consideration of the following description of a preferred embodiment of the invention which will now be described in connection with the accompanying drawings.

Referring therefore now to the drawings:

FIG. 1 is a front elevational view of a glare shielding device constructed in accordance with the present invention;

FIG. 2 is a sectional view taken along lines 2-2 of FIG. 1 looking in the direction indicated by the arrows;

FIG. 3 is a partially fragmented side elevational view taken along lines 3-3 looking in the direction of the arrows in FIG. 1;

FIG. 4 is a fragmented view taken along lines 4-4 of FIG. 1 looking in the direction indicated by the arrows;

FIG. 5 is a partially fragmented top plan view of the shielding device and illustrates the integral one piece construction thereof which facilitates its manufacture by conventional molding practices;

FIG. 6 is an enlarged fragmented view which illustrates the interrelation which exists between the temple brow bar and spacer support for the light impeding members;

FIG. 7 is a sectional view taken along lines 7-7 of FIG. 4;

FIG. 8 is a sectional view taken along lines 8-8 of FIG. 5; and

FIG. 9 is a somewhat diagrammatic view of the two shields and illustrates the geometrical relations which they bear to each other and to the nose piece.

Referring now more particularly to the several views wherein like parts are identified by like reference numerals, a preferred embodiment of the invention is illustrated at 10 as comprising a unitary structure molded in one piece of polypropylene or other opaque or translucent synthetic resin. However, it may also be constructed by other processes and of other materials. For example, it may be made of paperboard or pressed pulp board which is stamped or cut substantially to the shape hereinafter more particularly described. It may also be fabricated of light metal.

As illustrated by FIG. 5, a glare shielding device 10 according to the invention comprises a brow bar portion 12 having a length sufficient to extend across the average wearer's face above his eyes. This brow bar portion 12 includes an integral nose piece 14 which is centered on its underside and by which the device may be rested on the wearer's face. At either end of the brow bar are integrally hinged temples 16. Both the brow bar 12 and the two temples 16 are of thin sheet like construction which allows limited longitudinal flexing while imparting shape retention properties thereto in the transverse direction. The rear surface of the brow bar is flat since this allows the brow bar to be located close to the forehead and to have substantial wide engagement therewith above the eyes and particularly through the nasal region. The underside of the brow bar on either side of the nose piece 14 may be cut out or recessed as at 18 to provide clearance areas for the lenses of spectacle wearers. A most stable structure when worn is thus achieved and the engagement of the brow bar with the wearer's forehead also provides a reference point with which the light impeding shields 28 may be related as hereinafter described. The inner surface of the temples may also be flat; however, by molding with a raised section 12a and 17a along the length of their outer surfaces, the strength and rigidity of the temples and brow bar can be increased.

Although the temples 16 could be hinged to the ends of the brow bar 12 in conventional manner, it is preferred that the temples be molded integrally with the brow bar and narrow vertical sections 20 relieved at the juncture of the temples 22 to the respective ends of the brow bar 12 along which the temples are capable of hinging (Figure 8). Usefully the underside of the integral nose piece 14 is given an arcuate shape so that it will comfortably engage about the nose and a rib 22 (Figure 3) may be also formed on its rear side in the molding process to increase the bearing surface contact of the nose piece with the wearer's nose.

At 24 is a rectangular-shaped element which serves to support the mentioned pair of light impeding shields 28. As shown in FIG. 5 and considered also with FIG. 7, and FIG. 1, spacer element 24 has a length corresponding to that of the brow bar 12 and one edge thereof is hinged at selected intervals to the adjacent upper edge of said brow bar as by relieved portions 26 (FIG. 7) which permit the spacer element 24 to be folded on said hinges 26 into a forwardly projecting right angular relation to the plane of the brow bar as illustrated by FIGS. 2

and 3. The light impeding shields 28 are rigidly united to the forward edge of the spacer element in the molding so that they maintain a substantially right angular relation to the spacer element from which they depend. If desired, the central area of the rectangular spacer element may be omitted as is illustrated at 30 in FIG. 5.

Referring now to FIG. 5, it will be seen that during molding, a projection 32 is provided on the inner end of both temples which extends forwardly of their associated hinge constituting relieved section 20. As illustrated by FIGS. 4 and 6, said projection 32 terminates in an inwardly turned end portion 34 and, as shown in FIG. 5, a depending pin 36 is located in each of the two adjacent corners of the rectangular spacer element 24 which align with the relieved sections 20 on which the temples hinge. With the spacer element 24 folded on its hinges 26 into the right angular relationship illustrated by FIGS. 2 and 3, said projections 32 of the temple catch about said depending pins 36 which thereby constitute a biasing point or stop which limits the pivoting of the temple 16 about their hinge connection 20 and so influences the resilient engagement of the temples against the sides of the wearer's head. Preferably the outer ends 38 of the two temples are inwardly deflected and their inner surfaces provided with spaced ridges 40 and/or a small node or knob 42 at the outer end thereof to impart a non-slip character to the head engagement of the temples with the wearer's head. The supporting frame represented by the brow bar and temples is thus securely and stably supported on the wearer's head.

Catching of projections 32 about pins 36 also serves to locate the two light impeding shields 28 in a desired spaced parallel relation with the plane of the brow bar. As shown in FIG. 3, projection 32 has a flat upper surface 42 on which the spacer element 24 rests to resist any downward pivoting of the spacer element 24 about its hinge connections 26. The grip of said catch members on pins 36 under the urging of the outwardly deflected temples, when the device is worn, also resists accidental upward hinging of spacer element 24 on its hinge connections 26.

Referring to FIG. 9 and also FIG. 3, the two light impeding shields 28 are supported by spacer element 24 in front of the brow bar 12 and laterally offset from recesses 18 thereof so that the shield's are not in line with the motorist's eyes to effect his straight ahead vision but only inhibit light coming in at an angle, as from the headlights of oncoming traffic in the adjacent lane. Thus, as shown in FIG. 1, one of the two shields 28a is substantially centered between the two eyes and over the nose piece although slightly off center therefrom. The other shield 28b is positioned at the end of the brow bar, which is closer to the lane containing the oncoming traffic. As shown in FIG. 9, centers x of the two shields 28 are spaced apart a distance corresponding to the spacing of centers Y in FIG. 1 which may be considered to be the pupillary distance of the device. Thus each shield will have the same angular disposition to the line of vision of the wearer's eyes with which it is associated, assuming that the pupillary axes of the wearer's eyes also coincide with Y. The pupillary distance of individuals, however, vary considerably, for example between a maximum of 3.2 inches and a minimum of 2.2 inches. However, by taking into consideration the other dimensions of the shields 28, it is possible to select a center-to-center spacing for the two shields which will accommodate most individuals within the above mentioned range of pupillary distances to provide the desired impeding of glare from the headlights of oncoming traffic. Where dimensions a and b in FIG. 9 which represent the maximum width and height of the two light impeding shields 28 approximate 0.95 inches and the spacing of the shields from the brow bar represented by f is 1.8 inches, then it has been found convenient to space the shields so that their center-to-center spacing represented by p is about 2.55 inches.

It will be appreciated that distance a is a variable and will depend on the height at which the top edge of the brow bar is to be located. It is important that said distance a suffice to

locate the bottom edge 46 of the shields substantially at or only slightly below the normal or horizontal line of vision of the wearer. Thus if the two Y's in FIG. 1 are considered to indicate the pupillary axes of the wearer's eyes, then the bottom edge of the two shields 28 should either coincide with, but preferably extend slightly below, a plane including said pupillary axes Y.

As illustrated in FIG. 9, the opposed sides 44 of the two shields 28 are in converging relation and the bottom edge 46 of the shields is given a rounded shape corresponding to one-half of a circle having a radius c centered about x. Preferably sides 44 of the two shields are so sloped as to merge into the rounded bottom edge of the shield substantially at their horizontal diametric chord represented at k in said FIG. 9. Actually only a small portion of the two shields immediately adjacent the bottom edge thereof is utilized to impede the passage of light from the headlights of the oncoming traffic directly into the wearer's eyes. It is important therefore that the bottom edges of the shields be precisely located. By selecting a converging shape for the two sides of the shields it is possible to provide a wide juncture with the spacer element 24 to maintain this alignment and precise location. The converging of the two sides of the shield does not disturb the location of the bottom edge of the shields but does permit the angle of the wearer's straight-ahead vision of his two eyes to be increased so that the shields do not materially encroach upon or interfere with the wearer's vision of the lane in which he himself is driving. The converging shape of the two shields and their forward spacing of the brow bar thus permits both eyes of the wearer to have a substantially full angular range of vision which is substantially uninterrupted except for that small area adjacent the center of the bottom edge of the two shields and which is precisely located to impede the passage of light from the headlights of the oncoming traffic. The wider upper portion of the shields 28 also shades the eyes against glare from overhead street lights and the like.

It has been the inventor's experience that distance f is critical. If shields 28 are located too close to the wearer's eyes they become disconcerting as well as seriously hampering his lateral vision and tend to introduce headaches or nausea to the wearer. On the other hand if the shields are placed too far from the wearer's eyes, the device becomes cumbersome and uncomfortable when worn. A spacing of the shields of about 1.8 inches forwardly of the brow bar appears to be a good one. At this spacing of the shields, if the bottom edge of the shields is rounded on a radius c of about 0.43 inches and if shield 28a is also located so that it is off center of the brow bar about 0.15 inches as indicated at e, the inventor finds that there is sufficient area adjacent the bottom of the two shields to impede the passage of light to the wearer's eyes whether the oncoming traffic in an adjacent lane is a mile or more away or is only a few feet away. Furthermore, the wearer retains uninterrupted straight ahead vision of his own lane as well as retaining most of his lateral vision and this appears to be true whether the wearer has a pupillary distance of exactly 2.55 inches or one that is more closer to the minimum or maximum of the above recited range.

As already mentioned, the device is molded of either opaque or translucent material. Material of a translucent nature, however, is to be preferred since if shields 28 are translucent they are able to diffuse light from the headlights of the oncoming traffic. This has the advantage that the viewer does not lose sight of the approaching vehicle, but is able to follow its course. The surfaces of the structure may be either polished or unpolished. Advantageously, however, the front surface of the brow bar and nose piece, as well as the under surface of the spacer 26 should be given a matte finish which will discourage light reflections into the wearer's eyes. On the other hand, the surfaces of the two shields 28 are preferably polished since the shields will therefore be able to impede light by reflection as well as by color absorption or filtering and through diffusion by reason of their translucent character.

It will be understood that the devices are conventionally worn in the manner of spectacle frames and that the wearer is able to sit in his normally erect position with his chin up and his eyes focused on his lane ahead. He, however, retains substantially his full range of vision, substantially uninterrupted. Under some circumstances, as when driving into the sun, the wearer may find it advantageous to slightly cock his head a degree or two away from the sun or the adjacent lane containing the approaching traffic. However, he can conveniently do this because the shields occupy such a small fraction of his angle of vision and even in this instance he will have substantially a full range of straight ahead vision. When the device is molded of polypropylene it is extremely light weight and by reason of its construction it firmly and stably fits on the average wearer's head. Accordingly after even a short interval of wear the viewer becomes accustomed thereto and is able to enjoy impeded full vision of the road ahead and with a minimum of tilting or accommodation to occlude the headlights of the oncoming traffic, but which he is able to do naturally and more or less unconsciously.

As thus described it will be apparent that all the recited objects, advantages and features of the invention have been demonstrated as obtainable in a highly practical manner.

Therefore having described my invention, I claim:

1. A glare shielding device comprising a brow bar to extend across the wearer's forehead above his eyes having an intermediately located nose bearing portion and temples hingedly connected to the opposite ends of said brow bar, a forwardly disposed spacer member hinged to said brow bar, the spacer member having a pair of depending pin-like projections adjacent the two ends of the brow bar, and the temples having catch means for supporting the spacer member in a fixed forwardly projecting angular relation to the brow bar, said catch means comprising portions of the temples which project forwardly of the temple hinge connections to the end of the brow bar and releasably engage about said pin-like projections so as to resist further hinging of the spacer member relative to the brow bar and to increase the resilient bearing engagement of the temples with the wearer's head, and a pair of depending light impeding members secured to said forwardly projecting

spacer member, one of said light impeding members being thereby located forwardly of the nose bearing portion and the other light impeding member forwardly of one end of the brow bar.

5 2. A glare shielding device as claimed in claim 1 wherein the brow bar has recessed portions in its lower edge which provide clearance for the wearer's spectacle frames.

3. A glare shielding device as claimed in claim 1 comprising a one piece integrally united member of shape-retaining material, the forwardly projecting spacer member and the temples being hinged to the brow bar by relatively thin narrow flexible sections along which the spacer member and temples readily fold relative to the brow bar, the light impeding members being integrally united to the spacer member at right angles thereto.

10 4. A glare shielding device as claimed in claim 3 wherein the device, including the light impeding members, is of translucent plastic material.

5. A glare shielding device as claimed in claim 4 wherein the 20 brow bar and spacer member have dull finish surfaces.

6. A glare shielding device as claimed in claim 1 wherein the depending light impeding members each have a rounded bottom edge and downwardly converging side edges.

7. A glare shielding device as claimed in claim 1 wherein the 25 light impeding members have a center to center spacing corresponding to the pupillary distance of the average wearer and the bottom edge of said light impeding members is at or immediately below a plane including the wearer's pupillary axes when the device is properly worn.

30 8. A glare shielding device as claimed in claim 1 wherein the center-to-center spacing of the light impeding members is about 2.55 inches, the rounded bottom edge of the members is on a radius of about 0.43 inches, the width of the light impeding members at their connection to the spacer member is greater than twice the radius of said rounded edge, the light 35 impeding members are spaced about 1.8 inches forwardly of the brow bar, and the center of the first one of said light impeding members is about 0.15 inches offset from the center line of the brow bar and nose bearing portion.
